CLAIM

(57) We claim the ornamental design for a bowl, as shown and described.

DESCRIPTION

FIG. 1 is a perspective view of the bowl;
 FIG. 2 is a side view thereof, the opposite side, the front and the rear being identical;
 FIG. 3 is a top view thereof; and,
 FIG. 4 is a bottom view thereof.
 The broken lines represent a portion of the structure that forms no part of the claim.
